UNITED STATES PATENT OFFICE.

CHARLES W. COOK, OF EVANSVILLE, INDIANA.

BOTTLE-CAP.

No. 876,149.

Specification of Letters Patent.

Patented Jan. 7, 1908.

Application filed April 5, 1907. Serial No. 366,541.

To all whom it may concern:

Be it known that I, CHARLES W. COOK, a citizen of the United States, residing at Evansville, county of Vanderburg, and State 5 of Indiana, have invented certain new and useful Improvements in Bottle-Caps, of which the following is a specification.

My invention relates to bottle caps.

The ordinary bottle cap comprising a 10 metal shell adapted to be crimped around the mouth of the bottle and a cork disk within said shell, is quite defective in that it permits leakage, which is largely due to the fact that the cork disk does not properly seal 15 the mouth of the bottle.

A further defect of the ordinary bottle cap is that the shell is sufficiently springy so that it does not properly hold itself on the bottle mouth, which also permits leakage.

20 The present invention seeks to remedy the foregoing defects by the provision of a bottle cap having a shell provided with an off-set part which greatly strengthens the shell and, further, by the provision, in connection with 25 the improved shell, of a gasket located between the off-set part of the shell and the crimped part thereof adapted to bear against the mouth of the bottle when the cap is applied and to be expanded by the application 30 of the cap to the bottle and thereby made to very closely conform to the bottle mouth and produce a perfectly air-tight joint.

In carrying out the invention, I provide a 35 bottle cap shell having a central circular depressed or off-set part which defines a groove or channel between itself and the crimped part of the cap, and seat within the said channel, a pliable gasket, the specific construction and arrangement of such parts being set forth in detail hereinafter.

In the accompanying drawings: Figure 1 is a section of a bottle equipped with my improved cap; Fig. 2, a detail plan of the cap; Fig. 3, a section through the cap; Fig. 45 4, a bottom view of the cap; Fig. 5, details of the gasket and Fig. 6, details of the facing.

The neck of an ordinary bottle is shown at 1, the same having the usual bead 2 at its mouth so that the cap may be crimped there- 50 around.

The metal cap or shell 3 differs from those heretofore used in that it is provided with a

central circular depression or off-set part 4, which has an inner inclined wall 5, defining between said wall and the crimped part 6 of the 55 shell or cap, a circular channel or groove 7.

Seated within the channel 7 is a gasket 8 of rubber or other soft and pliable material which is preferably provided with an annular ring or facing 9. This facing 9 is of tin-foil 60 or sheeting. The facing 9 may be dispensed with if desired.

Normally the gasket 8 is of such width that it does not quite fill the channel 7, but when the cap is applied to the mouth of the 65 bottle and crimped around the bead 2, the bead 2 by its pressure against the gasket 8, expands it so that it conforms perfectly to the inner wall of the crimped wall 6 and to the wall 5 and also to the bead 2, the parts 70 being so constructed that a portion of the gasket is forced against the inner surface of the bead 2.

The depressed or off-set part 4 gives the 75 cap relatively enormous strength and prevents buckling and this insures a tight fit on the bottle mouth and prevents leakage or entrance of air in its association with the gasket 8, which forms an air-tight joint or seal with the mouth of the bottle. 80

The pliability of the covering 9, if used, causes it to conform perfectly to every point of the surface of the bead 2.

Having thus described my invention, what I claim as new and desire to secure by Letters Patent, is:—

A bottle cap consisting of a shell having a depressed central part, an outer circular wall adapted to be crimped around the mouth of the bottle, said wall and depressed part defining an intermediate annular channel, and an annular expandable gasket lying in said channel and of less width than said channel which is adapted to be expanded by the action of crimping the cap on the bottle to form 95 a seal, exposed to the fluid within the bottle, between the cap and bottle mouth.

In testimony whereof, I hereunto affix my signature in presence of two witnesses.

CHARLES W. COOK.
